BOTTLE CAP REMOVER

Melville D. Truesdale, Fairfield, Conn.

Application March 3, 1937, Serial No. 128,845
Renewed October 19, 1939

10 Claims. (Cl. 65—46)

My invention relates to bottle cap removers and more particularly has reference to bottle cap removers which will prevent the spilling or spurtng of the liquid contents upon the operator.

It is well known that carbonated beverages have a tendency to spurt upwardly when the cap is removed and often soil the clothes of the operator. Various devices have heretofore been devised to overcome the aforementioned difficulty but the majority of these devices have usually been too expensive to manufacture, difficult to operate, or very inefficient.

An object of my invention is to overcome the aforementioned defects in bottle cap openers.

Another object of my invention is to provide a bottle opener which is cheap to manufacture, positive in operation, and highly efficient.

A still further object of my invention is to provide a bottle cap opener which will prevent any danger of the liquid being spurted upon the user.

With these and other objects in view, which may be incident to my improvements, the invention consists in the parts and combinations to be hereinafter set forth and claimed, with the understanding that the several necessary elements comprising my invention may be varied in construction, proportions and arrangements, without departing from the spirit and scope of the appended claims.

In order to make my invention more clearly understood, I have shown in the accompanying drawings means for carrying the same into practical effect without limiting the improvements in their useful applications to the particular constructions which, for the purpose of explanation, have been made the subject of illustration.

In the drawings:

40 Figure 1 is a top plan view of my bottle opener.

Figure 2 is a bottom view of the device shown in Figure 1.

Figure 3 is a view taken along the lines 3—3 of Figure 1.

45 Figure 4 is a view taken along lines 4—4 of Figure 3.

Figure 5 is a view taken along the lines 5—5 of Figure 3.

50 Figure 6 is a sectional elevational view showing my device at the beginning of the operating cycle.

Figure 7 is a sectional elevational view showing my device after the cap has been removed.

55 Figure 8 is a sectional elevation showing my

device after an unusually large quantity of liquid has spurted from the bottle.

Figure 9 is a view taken along the lines 9—9 of Figure 6.

Referring to the drawings and more particularly to Figure 1 in which like numerals designate similar parts, there is shown a bottle cap remover comprising a hollow circular body portion 1. The body portion 1 flares outwardly at its lower end as at 2 and terminates in an annular bead portion 3.

A hollow handle 4 is flared into the side wall of the body portion as at 5. As shown in Figure 3, the handle 4 is provided with a closed upper portion 6 which is of sufficient length to permit the thumb of the operator to rest thereon. An aperture 7 in the side wall of the body portion affords communication between the interior of the body portion and the interior of the handle 4. The extremity of the handle is closed as at 8 and as will later become apparent the interior of the handle is employed as a spout for pouring off large discharges of liquid. The handle is also downturned as at 9 affording a stop for the small finger of the user's hand.

The body portion 1 is provided with a depending transverse rib 10, which divides the interior of the body portion into compartments 11 and 12. As shown in Figure 4, the body portion is provided with offset angular ribs 12 and 13. The ribs 12 and 13 serve to center the neck of the bottle when inserted within the ring portion.

A ledge 14 is formed in the side wall of the ring portion 1 opposite the aperture 7. A hook 15 for removing a bottle cap is secured to the ledge 14 by a screw 16 which is fitted through an aperture 16' provided in the wall of the ring portion.

As shown in Figure 3, a section of transparent material such as Ponalite or a similar molded plastic 17 is adapted to cover the section 11. The transparent material is adapted to fit into a pocket 18 provided in the rib 10 and under a lip 19 formed in the hook 15. The transparent material is so positioned as to deflect the liquid away from the operator.

A rubber diaphragm 20 having a central aperture 21 is positioned around the bead 3 of the ring portion 1. The aperture 21 is provided with an inner peripheral bead 22. The section is of sufficient size as to permit the neck of a bottle to be inserted therein. Moreover the diaphragm will provide a liquid proof seal thereby preventing any liquid from running down the neck of the bottle.

An arm 23 carrying an expanding ring 24 is pivoted as at 25 in ears 26 provided on the lower face of the handle 4. The arm 23 is adapted to move the ring 24 into engagement with the 5 diaphragm for enlarging the size of the aperture 21 thereby permitting the cap to fall therethrough after it has been removed from the bottle.

The operation of my device is clearly depicted 10 in Figures 6 to 8, inclusive. Referring to Figure 6 it can be seen that the neck 26 of a bottle 27 is inserted through the aperture 21 of the rubber diaphragm 20. The bottle cap 27' is fitted over the hook 15. The transverse rib 10 will serve as 15 a fulcrum for the cap and the annular ribs 12 and 13 will center the bottle with respect to the hook. Downward pressure is then exerted upon the handle and the cap will thereby be removed. After the cap is removed the expanding ring 24 20 is moved upwardly by means of the arm 23.

The expander ring will increase the diameter 25 of the aperture 21 and the cap will fall therethrough. However, the diaphragm will form a gutter around the lower edge of the body portion and will hold the liquid until the device is turned upside down at which time the liquid will be 30 removed through section 12.

If so desired, the aperture 21 in the rubber 35 diaphragm need not be of sufficient diameter to permit the cap to fall through after it has been removed. In such case both the liquid trapped in the gutter and the cap can be removed through the section 12 by inverting the device.

In the event there is an unusually large 35 discharge of liquid after the cap is removed, it can be seen by referring to Figure 8 that after the liquid has filled the body portion it will flow through the aperture 7 into the hollow handle 4 and will be discharged through the open portion 40 thereof. It will be appreciated that under such circumstances the handle will act as a spout and permit the removal of an excessive amount of liquid before lifting the expander ring 24 and removing the cap from the body portion.

45 From the foregoing description, it is apparent that I have provided an efficient, durable and inexpensive bottle cap opener. Furthermore, there is no possibility of the liquid spurting upon the operator when the cap is removed.

50 While I have shown and described the preferred embodiment of my invention, I wish it to be understood that I do not confine myself to the precise details of construction herein set forth by way of illustration, as it is apparent that 55 many changes and variations may be made therein, by those skilled in the art, without departing from the spirit of the invention, or exceeding the scope of the appended claims.

I claim:

60 1. A bottle closure opener comprising a hollow body portion adapted to receive a bottle neck, a hook within the body portion over which the cap fits, a transparent guard disposed over one of the 65 open ends of said body portion to prevent the spurting of the liquid from the body portion when the cap is removed and a rubber diaphragm fitted around the other end of the body portion to prevent the liquid from running down the neck of the bottle, said diaphragm provided with an 70 aperture through which the bottle neck extends.

2. A bottle closure opener comprising a hollow body portion adapted to receive a bottle neck, a hook disposed within the body portion over which the cap fits, a transparent guard disposed over 75 one of the open ends of the body portion to pre-

vent the spurting of the liquid from the body portion when the cap is removed, a rubber diaphragm fitted around the other end of the body portion, an aperture in the diaphragm through which the bottle neck extends, and means to expand the diaphragm to form a gutter to trap the liquid after the cap is removed. 5

3. A bottle closure opener comprising a hollow body portion adapted to receive a bottle neck, a hook disposed within the body portion over 10 which the cap fits, a guard disposed over one of the open ends of the body portion to prevent the spurting of the liquid from the body portion when the cap is removed, a rubber diaphragm fitted around the other end of the body portion, 15 an aperture in the diaphragm through which the bottle neck extends, and means to expand the diaphragm to form a gutter to trap the liquid after the cap is removed.

4. A bottle closure opener comprising a hollow 20 body portion adapted to receive a bottle neck, a handle for the body portion, a hook disposed within the body portion over which the cap fits, a guard positioned over one of the open ends of the body portion to prevent the spurting of 25 the liquid from the body portion when the cap is removed, a rubber diaphragm fitted around the other open end of the body portion, an aperture in the diaphragm through which the bottle neck extends and means pivoted to the handle 30 to expand the diaphragm to form a gutter to trap the liquid after the cap is removed.

5. A bottle closure opener comprising a hollow body portion adapted to receive a bottle neck, a cap engaging means secured within the body 35 portion, a guard disposed over one of the open ends of the body portion to prevent the spurting of the liquid from the body portion when the cap is removed, means within the body portion 40 to center the neck of the bottle with respect to the cap engaging means, and a rubber diaphragm fitted around the other end of the body portion, said diaphragm having an aperture through which the bottle neck extends.

6. A bottle closure opener comprising a hollow 45 body portion adapted to receive a bottle neck, a handle for the body portion, a cap engaging means secured within the body portion, a guard positioned over one of the open ends of the body portion to prevent a spurting of the liquid from 50 the body when the cap is removed, means within the body portion to center the neck of the bottle with respect to the cap engaging means, a rubber diaphragm fitted around the other open end of the body portion, an aperture in the diaphragm 55 through which the bottle neck extends and means pivoted to the handle to expand the diaphragm to form a gutter to trap the liquid after the cap is removed.

7. A bottle closure opener comprising a hollow 60 body portion adapted to receive a bottle neck, a handle for the body portion, a hook within the body portion over which the cap fits, a transparent guard disposed over one of the open ends of the said body portion to prevent spurting of 65 the liquid from the body portion when the cap is removed, a rubber diaphragm fitted around the other end of the body portion and having an aperture through which the bottle neck extends, and an arm pivoted to the underface of the handle, said arm being adapted to expand the diaphragm to form a gutter to trap the liquid after 70 the cap is removed.

8. A bottle closure opener comprising a hollow body portion adapted to receive a bottle neck, a 75

handle for the body portion, a hook within the body portion over which the cap fits, a transparent guard disposed over one of the open ends of the said body portion to prevent spouting of the liquid from the body portion when the cap is removed, a rubber diaphragm fitted around the other end of the body portion and having an aperture through which the bottle neck extends, an arm pivoted to the underface of the handle, and an expanding ring carried by said arm and adapted to expand the diaphragm to form a gutter to trap the liquid after the cap is removed.

9. A bottle closure opener comprising a hollow body portion adapted to receive a bottle neck, a handle for the body portion, a cap engaging means secured within the body portion, a guard positioned over one of the open ends of the body portion to prevent a spouting of the liquid from the body when the cap is removed, means within the body portion to center the neck of the bottle

with respect to the cap engaging means, a rubber diaphragm fitted around the other open end of the body portion, an aperture in the diaphragm through which the bottle neck extends and means pivoted to the underface of the handle to expand the diaphragm to form a gutter to trap the liquid after the cap is removed. 5

10. In a bottle closure opener, a hollow body portion adapted to receive the neck of a bottle, a hook secured within the body portion over which the cap fits, means within the body portion to center the neck of the bottle with respect to the hook, a transparent guard positioned above said hook to prevent spouting of the liquid from the body portion, and resilient means associated with the lower portion of said body portion to prevent the liquid from running down the neck of the bottle. 15

MELVILLE D. TRUESDALE. 20
